UNITED STATES PATENT OFFICE.

HENRY H. HILLIER, OF PASADENA, CALIFORNIA.

FIRE-ALARM SYSTEM.

No. 882,758.

Specification of Letters Patent. Patented March 24, 1908.

Application filed April 13, 1907. Serial No. 368,111.

To all whom it may concern:

Be it known that I, HENRY H. HILLIER, a citizen of the United States, residing at Pasadena, in the county of Los Angeles and State of California, have invented new and useful Improvements in Fire-Alarm Systems, of which the following is a specification.

My invention relates to a fire alarm system which is especially adapted to be used in small towns where a telephone system has been previously installed.

Heretofore it has been the practice to install special fire alarm boxes at different places on the streets, but the inconvenience of using these boxes has been so great that the telephone system, in case there should be one, has been used almost to the entire exclusion of the alarm boxes.

It is one of the objects of my invention to provide a system to be used in conjunction with a telephone system which will enable the operator at the central telephone station or central fire station to notify the fire station or stations of any fire of which said operator is made aware and of the exact locality of such.

It is also an object of my invention to provide a system by means of which the locality of the fire may be made known at the fire stations within very narrow limits and without excessive complications of apparatus.

A further object of my invention is to provide an apparatus which may be installed in a town already provided with a telephone system at a very nominal expense compared to the outlay necessary for a box fire alarm system.

A further object of my invention is to provide a system which will immediately give an alarm which is distinguishable from the fire alarms upon any accident to the system itself.

A further object is to provide a signaling device which will repeat the alarm signal as many times as is desired.

A further object is to provide a signaling device which is simple in operation, thus providing against any mistakes on the part of the operator.

I accomplish these objects by means of the system described herein and illustrated in the accompanying drawings, in which:—Figure 1— is a diagrammatic view of my complete system as it is installed in conjunction with an existing telephone system. Fig. 2— is a plan view, parts being broken away for pur-

poses of illustration, of the signaling device. Fig. 3— is a fragmentary detail of a portion of the top of the signaling device showing the indicator plate thereon. Fig. 4— is a vertical longitudinal section of the signaling device taken on line 4—4 of Fig. 2. Fig. 5— is a vertical cross section of the signaling device taken on line 5—5 of Fig. 2. Fig. 6— is a vertical cross section of the signaling device taken on line 6—6 of Fig. 2. Fig. 7— is a plan view of the spring motor which is used to drive the signaling device. Fig. 8— is a longitudinal vertical section of the same taken on line 8—8 of Fig. 7. Fig. 9— is a detail of a fire station gong. Fig. 10— is a diagrammatic view of the signaling circuit and a cross section similar to Fig. 6 of a modified form of signaling device showing the arrangement for an open circuit system.

Referring to the drawings and more particularly to Fig. 1, 23 designates a central station, such as a telephone central station, which is conveniently communicated with by the general public. Located in central station 23 is a signaling device 24 connected by line wires 25 and 25' to gong 26 in fire station 27. Signaling device 24 is also connected to annunciator 28 in the fire station 27. By means of this system any fire alarm which is communicated to the central station 23 by means of a telephone system, or in any other manner, may be transmitted from the central telephone station to the fire station by means of signaling device 24 which will cause gong 26 in the fire station 27 to ring any predetermined number of times and thereby notify the fire station of any fire and its locality. Annunciator 28 is also adapted to show by a numeral the exact locality, so that in case the gong or its line wires should become disabled the annunciator would still notify the station. The circuit through gong 26 and line wires 25 and 25' is preferably normally closed, so that the current from battery 29 is normally flowing around said circuit and through signaling device 24 as will be hereinafter described. Signaling device 24 operates to open the gong circuit and the gong is so constructed that it will ring every time the circuit is opened. Annunciator 28 is connected to signaling device 24 by a cable 30 and branch wire 31, so that the circuit through the annunciator is normally open and signaling device 24 operates to close said circuit and thereby to operate annunciator 28.

I will now proceed with a detailed description of the signaling device.

40 designates a case which is provided with a cover 41 and in which the mechanism of the signaling device is placed. Cover 41 is made in two sections 42 and 43 having a slot 44 between them for a part of their length. Section 43 is provided with an indicator plate 45 which has notches 46 in its edge projecting toward slot 44. These notches 46 are numbered to correspond with the numbers of the different numbered localities of the town in which the system is installed.

10 Mounted in bearings 47 secured to the base of case 40 is a shaft 48. Shaft 48 is provided with a worm gear 49, through the medium of which it is driven by a spring motor which will be hereinafter described, and with a series of alternating disks of insulating material and metal 50 and 51. These disks are arranged one after the other on shaft 48 and are held between flanges 52 and 53 rigidly upon said shaft. Longitudinal bolts 54 (see Fig. 6) are also provided to clamp the disks together and thus to hold them rigidly on the shaft. Disks 51 (see Fig. 6) are provided with a plurality of notches in their peripheries which run below the surface of the adjacent insulating disks 50 and which are arranged in such manner as to correspond to some designated number. Each disk 51 is mounted directly beneath one of the notches 46 in indicator plate 45 on the top of the signaling device and is notched to correspond 30 with the number connected with that particular notch 46.

Mounted on a shaft 55 above and to one side of shaft 48, is a lever 56 which projects through slot 44 in cover 41 and is provided 40 on its upper end with a handle 57 by means of which its shank 58 may be pulled into any one of notches 46 in indicator plate 45, spiral spring 59 being adapted to move lever 56 in the opposite direction and out of notch 45 46. Lever 56 is provided on its lower end with a slot 60 which is adapted to receive a spring plate 61 extending horizontally over disks 50 and 51 to the side wall of case 40. Spring plate 61 is provided on its under side 50 with a wedge-shaped contact 62 which is adapted to be pressed against disks 50 and 51 by the action of the spring plate. The outer end of spring plate 61 is adapted to rest on any one of a series of contacts 63 secured to the side wall of the case and to which are connected the individual wires 64 of annunciator cable 30. Lever 56 is slidably mounted on shaft 55 by means of key 65 and longitudinal key-way 66 in the shaft.

60 Mounted on the end of shaft 48 is a composite disk 67 provided with a notch 68 (see Fig. 5) in its periphery. On the end of shaft 55 and directly opposite disk 67 is rigidly mounted a bell crank lever 69 whose 65 vertical arm 70 is provided with a lug 71

adapted to enter notch 68 in disk 67. Horizontal arm 72 of bell crank lever 69 carries a stud 73 provided at its end with a brake shoe 74 which is adapted when lug 71 is in notch 68 to contact with a friction wheel on the spring motor used to drive shaft 48 and thereby stop the motor as will be hereinafter described. Spiral spring 59 operates to press lug 71 into notch 68 so that whenever lug 71 is removed from notch 68 by the movement of lever 56 into one of the notches in the indicator plate, shaft 48 will be permitted to make but one revolution, lug 71 being forced into notch 68 by the action of spiral spring 59 and the rotation of the shaft 80 being stopped. The motor is also stopped at the same time by the action of brake shoe 74, so that any strain on the mechanism is obviated.

Disk 67 is provided with an insulating facing 75 through which a stud 76 attached to disk 67 projects. A spring contact 77 bears against disk 67 and a second spring contact 78 bears against insulating facing 75 in such a position as to contact with stud 76 whenever that stud comes to a position opposite the spring contact, and thereby to close the electrical connection between contacts 77 and 78. Stud 76 is so placed on disk 67 that it contacts with spring contact 78 when the device is in its normal position, or when lug 71 is in notch 68.

Spring contact 78 is connected by wire 79 to binding post 80 on the outside of case 40. Spring contact 77 is connected by wire 81 to binding post 82 on the outside of case 40. These binding posts 80 and 82 are connected to line wires 25 and 25' with battery 29 in the circuit, so that the circuit is normally closed through battery 29, line wire 25', 105 gong 26, line wire 25, binding post 80, wire 79, spring contact 78, stud 76, spring contact 77, wire 81, binding post 82, back to battery 29. When shaft 48 starts on its revolution, stud 76 revolves away from spring contact 78, thereby breaking the above circuit. But it is obvious that in order to let shaft 46 revolve, lug 71 must be pulled out of notch 68 and this necessitates lever 56 being pulled to the left in Figs. 5 and 6 which can only be 110 done by pulling said lever into one of the notches 46 in indicator plate 45. In order to pull lever 56 into one of these notches, lever 56 must be moved into position directly above one of the disks 51, so that contact 62 is bearing on that particular disk. Lever 56 is connected by a wire 90 (see Figs. 2 and 6) to binding post 80 and disks 51 are connected through shaft 48, disk 67 and spring contact 77 to binding post 82. Thus it will 115 be seen that the circuit through the line wires 25 and 25' and gong 26 will remain closed until some one of the notches in the periphery of disk 51 passes under contact 62 when the contact will be allowed to rest 120 125 130

momentarily on the insulating disks 50 on either side of disks 51, contact 62 being made wider than the thickness of a disk 51 as is shown in Fig. 4. Upon the passing of that 5 particular notch in the periphery of the disk, contact 62 will again contact with disk 51 and close the circuit until a subsequent notch in the periphery of disk 51 passes the contact when the circuit will again be 10 opened. The notches in the peripheries of disks 51 are arranged, so that by their successive passage of contact 62 and their consequent opening of the gong circuit they will ring the gong a number of times in such a 15 particular order as to notify the fire station immediately of the number which that particular disk represents, which is the number directly above it on the indicator plate 45. A space 91 is provided in the end of indicator plate 45 where lever 56 may rest when the device is not in use and annunciator contacts 63 are so arranged on the side wall of the case that spring plate 61 will not come 20 in contact with any of them when lever 56 is in this position. When, however, lever 56 is moved into one of the notches 46 in indicator plate 45, insulated contact 101 on the end of spring plate 61 will come into contact with the corresponding annunciator contact 30 63 and will close the electric circuit from battery 29 through binding post 82, wire 100, contact 101, contact 63, cable 30, annunciator 28, branch wire 31, line wire 25' back to battery 29, and thus operate the annunciator 35 in the usual manner to show the number corresponding to the number on the indicator plate against which lever 56 is placed.

I preferably employ a spring motor to drive the signaling device which is more 40 particularly shown in Figs. 7 and 8, but I do not limit myself to that particular class of motive power. It is provided with a flat helical spring 110 having ratchet winding mechanism, not shown, and mounted on a 45 shaft 111 which is provided with a large gear wheel 112. Gear wheel 112 meshes with pinion 113 on shaft 114 which extends outwardly from the spring motor across case 40 of the signaling device and has mounted 50 on it directly above shaft 48 a worm wheel 115 adapted to mesh with worm wheel 49 on shaft 48. By means of these devices shaft 48 is driven by spring 110. Gear 112 also meshes with pinion 116 on shaft 117 which is 55 provided with a large gear 118. Large gear 118 meshes with a pinion 119 on shaft 120 which carries on its outer end gear wheel 121 and brake wheel 122. Brake shoe 74 hereinbefore mentioned is adapted to contact 60 with brake wheel 122 and thereby stop the operation of the motor. Gear wheel 121 meshes with pinion 123 on a shaft 124 which carries a ball governor 125 of the friction type which is common in the motors of 65 talking machines. Regulating screw 126

is provided for regulating the speed of the motor and a squared shaft 127 is also provided to facilitate the winding of spring 110. The speed at which the motor may be run will depend upon the rapidity at which the 70 signaling circuit may be worked and also upon the distance between successive notches in the contact disks 51. In any event shaft 48 will be rotated very slowly.

In Fig. 9 I have shown a detail view of 75 a type of gong which may be used in my system, without limiting myself to this particular type. An electro-magnet 140 is mounted on the base 141 of the gong directly in front of armature 142 secured to double 80 pawl 143. Pawl 143 works in the teeth of ratchet 144 mounted on shaft 145, which shaft is driven by helical spring 146. Mounted on this shaft 145 is also a ratchet wheel 147 whose teeth are adapted to engage a lug 148 on a spring pressed arm 149. Arm 149 carries hammer 150 in such a position that it will strike gong 151, shown in dotted lines, whenever ratchet wheel 147 rotates 85 underneath lug 148. When the circuit from battery 29 is either opened or closed through the gong, electro-magnet 140 is de-energized or energized to operate pawl 143, permitting ratchet 144 to rotate a distance corresponding to one tooth, thereby ringing 90 gong 151 once. This operation is repeated whenever the circuit is opened or closed 95 through the gong.

In Fig. 10 I have shown a modified form 100 of disk 160 to be used in connection with an open circuit arrangement. Disk 160 is provided with projections 161 which correspond to the notches in disks 51 and contact 62 is adapted to close the circuit through battery 29 and an ordinary open circuited 105 gong 162 whenever one of these projections 161 come into contact with it. The periphery of disk 160 between the projections is lower than the periphery of the adjacent insulating disks 50 so that contact 62 will 110 normally rest on the peripheries of the insulating disks. Connected in series with the open circuit bell is also an open circuit relay 163 which is adapted to open local circuit 164 through a closed circuit gong 165 and 115 local battery 166 when the main circuit is closed. By means of this arrangement an open alarm circuit and a closed alarm circuit may be worked together.

It will be noted that I have produced a 120 system which is very simple in its construction and operation and which may be installed in a town of moderate size for very little cost where the outlay for a box fire alarm system would be very heavy. It will 125 also be observed that I have provided a system which, mainly on account of its simplicity, is very free from any accident or disorders, and, that should any occur, an alarm of one stroke will immediately be 130

sounded, as the signaling circuit is normally closed and any accident will open the circuit. It will also be noted that I have produced a system which may be used to notify a single fire station or any number of fire stations, as any number of gongs and annunciators may be connected in the signaling circuits and be operated by one signaling device which is located preferably at the central 10 telephone station. This location, however, is not necessary as the signaling device may be located at any place, such as the central fire station, which has telephonic communication with the different parts of the town 15 in which the system is located.

Having described my invention what I claim as new and desire to secure by Letters Patent is:—

1. In a fire alarm system, a signaling device comprising a case; a shaft rotatively mounted in said case; a spaced series of metallic disks rigidly mounted on said shaft having notches in their peripheries; a series of insulating disks mounted between said 25 metallic disks and having a diameter greater than the diameter of the bottom of said notches in the metallic disks and less than the diameter of the metallic disks; a contact adapted to follow the contour of the 30 metallic disks and rest on said insulating disks when it is in the notches of the metallic disks; and means to rotate said shaft and disks.

2. A signaling device comprising a case; a shaft rotatively mounted in said case; an indicator plate on the top of said case having designations thereon; a plurality of disks on said shaft, there being a disk located directly beneath each designation on said indicator 40 plate, and each of said disks being provided with notches in its periphery to correspond with the designation directly above said disk; a contact adapted to engage with the periphery of any one of said disks; means to 45 rotate said disk; and means to automatically release said rotating means when said contact is brought into a position to contact with any of said disks.

3. In a signaling device, a plurality of 50 rotative disks; a contact adapted to engage with any of said disks; means to rotate said disks; and means to lock said disks from rotation; and means to automatically release said disks when said contact is placed in engagement with one of said disks.

4. In a signaling device, a plurality of rotative disks; a contact adapted to engage with any of said disks; means to rotate said disks; means to lock said disks from rotation; means to automatically release said disks when said contact is placed in engagement with one of said disks; and means to lock said disks from rotation after one revolution thereof.

5. In a closed circuit signaling device, a

plurality of rotative notched disks; a contact adapted to engage with said disks; means to lock said disks from rotation until said contact is placed in engagement with said disks; an external signaling circuit of 70 which said disks and said contact form the terminals; and means to hold said circuit closed around said contact and disks while said disks are locked from rotation.

6. In a signaling device, a case; a shaft 75 rotatively mounted in said case; means to rotate said shaft; a plurality of notched contact disks rigidly spaced on said shaft; insulating disks between said notched disks, the diameter of said insulating disks being 80 less than the diameter of said notched disks and greater than the diameter of the bottom of said notches; a spring pressed contact of greater width than said notched disks and 85 adapted to engage with said disks, said contact and disks adapted to form the terminals of an electric circuit; a second shaft rotatively mounted adjacent and parallel to said first named shaft and on which said spring contact is slidably and non-rotatively mounted; a spring secured to said last named shaft 90 adapted to force said contact into engagement with said disks; a notched plate mounted on said case; an arm rigidly attached to said contact and adapted to be 95 placed in any one of the notches in said plate; a notched locking disk on said first named shaft; an arm rigidly mounted on said second named shaft provided with a lug adapted to enter the notch in said locking 100 disk and lock said first named shaft from rotation, said lug adapted to be removed from said notch when the arm on said contact is placed in one of the notches in said plate; a contact pin in said locking disk; 105 and a contact mounted in said case adapted to engage said pin when said disk is in its locked position, said contact pin and contact being connected in parallel with said notched disks and said first named contact.

7. A signaling device comprising a case; a shaft journaled in said case; an indicator plate on the top of said case having designations and notches thereon corresponding to each other; a plurality of disks on said shaft, 115 there being a disk located directly beneath each designation and notch on said indicator plate, and each of said disks being provided with notches in its periphery to correspond with the designation directly above; a spring 120 operated shaft mounted in said case; an arm mounted on said shaft and adapted to be moved longitudinally thereon to engage with any of the notches in said plate; a contact mounted on said arm and adapted to engage 125 with any of said disks; stationary contacts mounted in said case; a second contact mounted on said arm and adapted to engage with said stationary contacts; means to rotate said disk; means to lock said disk 130

from rotation, said means adapted to be disengaged upon the insertion of said arm in any one of said notches; a circuit leading through said first named contact on said arm 5 and said disk; and means to close said circuit around said disk while said disks are locked from rotation.

In witness that I claim the foregoing I have hereunto subscribed my name this 30th day of March, 1907.
